UNITED STATES PATENT OFFICE.

GEORGE E. W. STIVERS, OF NEW YORK, N. Y.

SHIFTING SEAT FOR VEHICLES.

SPECIFICATION forming part of Letters Patent No. 530,608, dated December 11, 1894.

Application filed May 17, 1894. Serial No. 511,607. (No model.)

To all whom it may concern:

Be it known that I, GEORGE E. W. STIVERS, a citizen of the United States, residing at New York, in the county and State of New York, have invented certain new and useful Improvements in Shifting Seats for Vehicles, of which the following is a full, clear, and exact description, such as will enable those skilled in the art to which it appertains to make and use the same, reference being had to the accompanying drawings.

This invention relates to improvements in that class of vehicles which are ordinarily termed driving traps. It particularly applies to a mechanism whereby a shifting seat may be adjusted to several different positions.

It has for its object the provision of such a mechanism whereby the shifting seat can be readily adjusted to a dos-a-dos position, in which position two adjustments are secured, one of which depends upon the back of the forward seat for its back support and the other depends upon its own back; to a position facing to the front; and finally to a position under the forward seat to leave the main body clear for the reception of bundles, parcels, &c.

It also has for its object a construction which is simple, cheap, substantial and by means of which the seat can be easily manipulated to its various adjustments.

Heretofore shifting seats of this class have been formed by supporting the seat proper upon legs or standards hinged to the floor or other portions of the vehicle, or the seats have been carried upon other mechanisms of a more or less complicated construction. In these instances, the supports are liable to get out of order, wear loose, are hard to operate, and are limited in the number of their adjustments, and often owing to their size, occupy so much room as to almost render the body unavailable to carry parcels, &c. In the present instance it is proposed to overcome these objections by doing away with legs or other similar supports. It is proposed to support the seat by forming in the sides of the body grooves with which projections extending from the ends of the seat can be placed in registration. In this way the seat, by means of the peculiarly formed grooves, can be variously adjusted to the several positions hereinbefore mentioned,

or moved out of the way beneath the front seat, thereby leaving the main body entirely free for the reception of parcels, &c.

The invention also consists in the novel construction, combination and arrangement of parts such as will be hereinafter fully described, pointed out in the appended claims, and illustrated in the accompanying drawings.

In the accompanying drawings, in which similar letters of reference designate corresponding parts, Figure 1 is a longitudinal vertical section of a vehicle embodying the invention, showing in full lines the seats in a dos-a-dos position, each having its own back support in an operative position. It also shows in dotted lines two other adjustments of the shifting seat. Fig. 2 is a similar view showing in full lines the shifting seat stowed away beneath the forward seat. In dotted lines other adjustments are shown. Fig. 3 is a transverse vertical section on the line 3—3 of Fig. 2. Fig. 4 is a detail sectional view showing portions of the shifting seat and the sides of the body, and the lugs projecting from the ends of the former and engaging with the grooves in the latter. Fig. 5 is a similar view, showing the locking bolts which are adapted to secure the seat in any of its adjusted positions. Fig. 6 is a detail view showing a plan of the shifting seat, the back being removed. Fig. 7 is a detail view, partly in section, showing the locking bolt and the lug adapted to engage with the groove formed in the side of the body. Fig. 8 is a detail perspective view, showing the inner face of one of the sides of the body.

Referring to the drawings by letter, A, A, designate the sides of the body of a vehicle, which may be of any construction suitable in the premises. In the present instance it is what is ordinarily termed a driving trap or carriage.

B designates the wheel well, and C the forward seat. The latter is supported upon raised portions of the sides A, A, being hinged at one end to one of the sides by the hinges c, c, and provided at its opposite end with lugs c', c', adapted to register with suitable sockets formed in the opposite side, whereby the seat will be firmly held in place. The

seat is provided with the customary back D. By having the seat hinged in this manner access to the rear seat can be easily had.

In each of the sides A, A, grooves e and f are formed. The groove e extends from a point immediately above the wheel well and below the front edge of the forward seat to the upper edge of the side to a point back of the front seat. The other groove, f, starts at a point situated at a considerable distance to the rear of the starting point of the first groove, but on the same level with the same. This groove extends to the rear and upward to the edge of the side to a point situated considerably in the rear of the upper end of the first mentioned groove. The grooves e and f are respectively provided with openings e' and f', which lead out of the said grooves. A slot or groove g is also formed in each of the sides A, A, near the upper edge and in the rear of the same. It is provided with an opening g', which leads to the top of the side. These grooves, e and f, are respectively provided with irons e² and f². The latter iron, f², is continued over the groove g. These irons may serve to simply protect the grooves and to serve no purpose in holding the shifting seat in place; but in the present instance they serve both to protect the grooves and to aid, in conjunction with the headed lugs projecting from the seat, in supporting and holding the latter. These irons may be either forged or cast, but preferably forged as a more finished appearance can be secured. These irons partly cover their respective grooves and each has an opening, or openings, which follows the path, or paths, of its respective groove, or grooves. The width of this slot is less than that of the grooves. The object of this will be explained farther on.

H designates the shifting seat, provided with a hinged back H'. Projecting from each end are lugs h, h', provided with heads h², h². These lugs are as far apart as the distance between the lower ends of the grooves e and f. It is also to be observed that the distances between the openings e' and f', and f' and g', is the same as the distance between the lugs h and h'. The purpose of these lugs is to support the seat by their respective registration with the grooves e, e, and f, f, and their engagement with the side irons partly covering the grooves; also by means of these lugs, in conjunction with the grooves e, e, f, f, and g, g, and the side irons, the several adjustments of the seat can be secured.

Assuming the seat to be in the position shown in dotted lines in Fig. 1, beneath the forward seat of the vehicle, to adjust it to a dos-a-dos position, it is slid to the rear, until the lugs reach the upper ends of their respective grooves, where the seat will take a horizontal position immediately back of the front seat and flush with the tops of the sides A, A. It is to be observed that the back of the shifting seat is folded under the latter during this adjustment. After being adjusted to this posi-

tion, an occupant of the seat can use the back rest of the forward seat. If it should be desired to adjust the seat so as to face the rear but to allow the use of its own back, the lugs h, h, are disengaged from the slots and the seat is turned on the lugs h', h', until the lugs h, h, pass through the openings g', g', and register with the grooves g, g. By so turning the seat, it is moved more to the rear, and the back brought into such a position that it can be used. When the shifting seat is used facing to the rear, the end gate is lowered to form a foot rest as shown in Fig. 1.

If it should be desired to have the seat facing to the front, it can be readily removed from the slots and turned and placed in the position shown by dotted lines in Fig. 2. When in this position the end gate is closed. From this latter position it can be quickly turned to a dos-a-dos position by releasing the lugs h', h' and turning the seat on the lugs h, h, until the former lugs engage with the slots e, e. From this latter position the seat can be shoved under the forward seat, as shown in Fig. 2.

The grooves f, f, and g, g, and the grooves e, e, if desired, can be extended beyond the openings leading into them so that when the seat is placed in position the lugs will be out of register with the said openings and thereby lessen the liability of displacement. Spring pressed bolts L, L, are provided so that the seat, by means of the same and suitably formed sockets, can be securely locked in place. These bolts are preferably seated in the edge of the seat so as to be easily accessible.

The end gate M is attached to the floor of the body by the hinges m, m, and it is provided with the chains m', m', whereby the gate can be lowered to form a foot rest when the seat is in either of the dos-a-dos positions. The gate is provided with the usual mechanism for securing it when closed.

The vehicle can be upholstered in any desired manner. It is to be observed that when the shifting seat is moved under the forward seat, there is considerable room between the two seats which can be utilized for the stowing away of cushions, and thereby leave the main part of the body free to receive bundles, &c.

While the device as above described is the preferred construction of the invention, yet it can be departed from to a considerable extent without departing from the spirit of the invention. For an instance, the grooves in the sides may traverse the latter differently, and differently formed irons may be used.

Having thus described my invention, what I claim, and desire to secure by Letters Patent, is—

1. In a vehicle, the combination of the sides of the body thereof, the said sides having inclined grooves traversing the inner faces thereof and horizontal locking grooves, and the shifting seat having projections adapted

to engage with and to move in the said grooves, substantially as described.

2. In a vehicle, the combination of the sides of the body thereof, the seat mounted on the forward ends of the said sides, the said sides having grooves formed in the inner faces of the same leading from beneath the first mentioned seat to the rear and to the top of the said sides, and the shifting seat provided with projections adapted to register with the said grooves, and to move therein, substantially as described.

3. In a vehicle, the combination of the sides of the body thereof, the seat movably mounted on the forward ends of the same, the said sides

having grooves formed in the inner faces of the same leading from beneath the first mentioned seat to the rear and to the top of the said sides, and also having locking grooves in their extreme rear upper edges, and the shifting seat having projections adapted to register with and to move in the said grooves, substantially as described. 20

In testimony whereof I hereunto subscribe my name in the presence of two witnesses.

GEO. E. W. STIVERS.
